UNITED STATES PATENT OFFICE

124,058

DESIGN FOR A SPRAYER OR SIMILAR ARTICLE

Rudolph Bernhardt, Chicago, Ill.

Application February 20, 1939, Serial No. 83,121

Term of patent 14 years

To all whom it may concern:

Be it known that I, Rudolph Bernhardt, a citizen of the United States and resident of Chicago, in the county of Cook and State of Illinois, have invented a new, original, and ornamental Design for a Sprayer or Similar Article, of which the following is a specification, reference being had to the accompanying drawing, forming part thereof. In the drawing

The dominant features of my design reside in the portions shown in full lines.

I claim:

The ornamental design for a sprayer or similar article, as shown and described.

RUDOLPH BERNHARDT.
